UNITED STATES PATENT OFFICE.

ALBERT F. SAUNDERS, OF SYRACUSE, NEW YORK, ASSIGNOR TO T. N. BENEDICT MFG. CO., OF EAST SYRACUSE, NEW YORK.

DESIGN FOR A SPOON.

Application filed September 15, 1926. Serial No. 19,073. Term of patent 3½ years.

To all whom it may concern:

Be it known that I, ALBERT F. SAUNDERS, a citizen of the United States, residing at 106 Rugby Road, city of Syracuse, county of Onondaga, and State of New York, have invented a new, original, and ornamental Design for a Spoon, of which the following is a specification, reference being had to the accompanying drawing, forming a part thereof, wherein—

The two Figures 1 and 2 are plan views of

the front and the back of a spoon showing my new design.

I claim:

The ornamental design for a spoon substantially as shown.

In testimony whereof, I have hereunto signed my name at East Syracuse, in the county of Onondaga and State of New York this 10th day of September, 1926.

ALBERT F. SAUNDERS.
